US00D756352S

(12) **United States Design Patent**
Matsuoka

(10) **Patent No.:** **US D756,352 S**
(45) **Date of Patent:** **** May 17, 2016**

(54) **NOTEBOOK COMPUTER HOUSING**

(71) Applicant: **Google Inc.**, Mountain View, CA (US)

(72) Inventor: **Yoshimichi Matsuoka**, Sunnyvale, CA (US)

(73) Assignee: **Google Inc.**, Mountain View, CA (US)

(**) Term: **15 Years**

(21) Appl. No.: **29/529,940**

(22) Filed: **Jun. 11, 2015**

Related U.S. Application Data

(62) Division of application No. 29/485,320, filed on Mar. 18, 2014, now Pat. No. Des. 734,319, which is a division of application No. 29/447,973, filed on Mar. 8, 2013, now Pat. No. Des. 702,224.

(57) **CLAIM**

The ornamental design for a notebook computer housing, as shown and described.

DESCRIPTION

FIG. 1 is a front perspective view of a notebook computer housing shown in an open configuration according to my design;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof;

FIG. 8 is a front perspective view of a notebook computer housing according to my design shown in a closed configuration;

FIG. 9 is a front view thereof;

FIG. 10 is a back view thereof;

FIG. 11 is a right side view thereof;

FIG. 12 is a left side view thereof;

FIG. 13 is a top view thereof; and,

FIG. 14 is a bottom view thereof.

Broken lines are environmental only and form no part of the claimed design.

1 Claim, 11 Drawing Sheets
